CARBURETOR

Milton E. Chandler, New Britain, Conn., assignor, by mesne assignments, to Niles-Bement-Pond Company, West Hartford, Conn., a corporation of New Jersey

Application August 13, 1943, Serial No. 498,471

10 Claims. (Cl. 123—119)

1

The present invention relates to carburetors for internal combustion engines for use on aircraft, and particularly to means for controlling the fuel to air ratio in such carburetors.

Internal combustion engines, such as those used in aircraft, operate most efficiently on a lean mixture of fuel and air. It is desirable, however, in order to secure the maximum power output of the engine, to operate on a somewhat richer mixture. Also, the engine runs cooler on a richer mixture, and hence it is desirable, when operating with adverse cooling conditions such as are encountered at high altitudes or during a climb, to operate the engine on a rich mixture.

Aircraft engines of conventional construction are usually provided with manual mixture controls whereby the pilot may shift from a lean to a rich mixture or vice-versa. It sometimes occurs that the pilot forgets to change the mixture control to correspond with the changing flight conditions he encounters. This may result in excessive fuel consumption if the mixture control is left in a rich position, or it may result in dangerous overheating of the engine if the mixture control is left in its lean position.

It is, therefore, an object of the present invention to provide means responsive to the flight conditions encountered by an aircraft for controlling the fuel to air ratio. Another object of the present invention is to provide means responsive to the rate of change of altitude of an aircraft for controlling the fuel to air ratio.

Another object is to provide means responsive to the quantity of air entering the carburetor to enrich the mixture of fuel and air when the quantity of air exceeds a predetermined amount.

A further object is to provide mixture control means which is operable in a plurality of stages.

A further object is to provide a multiple stage mixture control which operates to increase the fuel to air ratio in response to a flight condition of the aircraft, and which operates to additionally increase the fuel to air ratio in response to the quantity of air entering the engine.

Other objects and advantages of the present invention will become apparent from a consideration of the appended specification, claims, and drawing in which

Figure 1 is a somewhat diagrammatic illustration of a carburetor adapted for use with an air-

2

craft engine and provided with a mixture control arrangement embodying my invention.

Figure 2 is a graphical illustration of the relationship between the fuel and air ratio and air flow in the carburetor of Figure 1, and

Figure 3 illustrates an alternative form of control device which may be used in the carburetor of Figure 1.

In Figure 1, there is shown a carburetor body 10 thru which air flows from an inlet 11, thru a passage 12 to an outlet 13. In flowing thru the passage 12 the air passes thru a Venturi restriction 14, past a throttle 15, and a fuel discharge nozzle 16.

A second air passage connects the inlet 11 and the throat of venturi 14. This second air passage may be traced from the inlet 11 thru a plurality of impact tubes 17, whose open ends project into the inlet 11, a vent ring passage 18 interconnecting the impact tubes 17, a conduit 20, an expandible chamber 24 in a fuel regulator unit 25, a restriction 26, another expandible chamber 27 in the fuel regulator 25, a conduit 28, a chamber 33 and a conduit 34 to the throat of venturi 14.

A bellows 35 is mounted in the chamber 33, and operates a valve 36 which controls the flow of air from the conduit 32 into the chamber 33. The bellows 35 is preferably filled with nitrogen or other temperature responsive fluid, so that the position of valve 36 is determined by the temperature and pressure of the air in the chamber 33, and hence by the density of that air.

The valve 36 restricts the flow of air to the second passage just described in such a manner that the pressure differential between chambers 24 and 27 is an accurate measure of the mass of air going thru the passage 12. Errors due to changes in the density of the air with altitude and temperature, and also those errors due to the inherent limitations of a metering restriction of the Venturi type, are substantially eliminated by the operation of valve 36. This type of altitude and metering error compensation is more completely described and claimed in my co-pending

application Serial No. 490,281, filed June 10, 1943, now Patent Number 2,383,144.

The fuel passing thru the carburetor comes from a fuel pump or other source of fuel under pressure (not shown). From that source the fuel passes thru a conduit 37, the fuel regulator unit

25, a conduit 38, a jet system 40, an idle valve 49, a conduit 41, a pressure regulator 42, and a conduit 43 to the discharge nozzle 16.

The fuel regulator unit 25 comprises a housing 44, which is divided by three flexible diaphragms 45, 46, and 47 into four expandable chambers 48, 24, 27 and 50. The diaphragms 45, 46 and 47 are all attached to a valve stem 51, by any suitable means. The valve stem 51 carries a balanced valve 52 at its lower end. A compression spring 53 acting on the diaphragm 45 biases the stem 51 for movement of the valve 52 toward open position.

The pressure in chamber 50 is the same as that existing on the upstream side of the jet system 40. Chamber 48 is connected thru a conduit 54 to the conduit 41 on the downstream side of the jet system 40. The differential between these pressures is a measure of the quantity of fuel flowing thru the jet system. This pressure differential is transmitted to the chambers 48 and 50, as described above, where it acts thru the diaphragms 45 and 47 in a direction tending to close the valve 52. As previously pointed out, the pressure differential between chambers 24 and 27 is a measure of the mass of air flowing thru the passage 12. This air pressure differential acts on the valve 52 in an opening direction. It may be seen that the valve 52 is positioned in response to changes in the air pressure differential to produce a balancing change in the fuel pressure differential. Therefore, the valve 50 controls the quantity of fuel flowing thru the carburetor in accordance with the mass of air flowing thru the passage 12.

The idle valve 49 is provided to control the flow of fuel when the air flow is small, as when idling the engine. The idle valve 49 is connected to the throttle 15 for concurrent operation therewith, by means of a linkage generally indicated at 59. At low air flows, it has been found that the pressure differential between chambers 24 and 27 tends to be erratic. The spring 53 and idle valve 49 have been provided to control the fuel flow at such times. At low values of air flow, the force of spring 53, urging the valve 52 toward open position, overrides the force due to the pressure differential between chambers 24 and 27, thereby moving valve 52 in an opening direction. The connection between the throttle 15 and valve 49 is so designed that the valve 49 is retracted to a position where it does not appreciably restrict the fuel flow when the throttle is out of a range of positions near the closed position, sometimes termed the idling range. As the throttle moves into the idling range, the valve 49 is moved to restrict the fuel flow, and this restriction of the fuel flow becomes greater as the throttle moves toward closed position. In effect, the control of the fuel flow is transferred from the air flow responsive regulator 25 to the throttle-controlled idle valve 42 when the latter is in its closed or nearly closed positions.

Fuel entering the jet system 40 from the conduit 38 passes into a chamber 55. The fuel may flow out of the chamber 55 either thru a fixed restriction 56, a restriction 57 controlled by a poppet valve 58, or a restriction 60 controlled by a valve 61. Fuel flowing thru the restrictions 57 and 60 must also pass thru another fixed restriction 62 before passing out of the jet system 40 into the conduit 41.

The poppet valve 58 is biased to closed position by a spring 63, and is opened against the action of this spring only when the pressure differential

across the jet system 40 becomes large enough to overcome the spring. Therefore, the valve 58 operates to automatically enrich the fuel and air mixture supplied to the engine when the load on the engine is high.

The valve 61 has a main body portion of cylindrical form whose end cooperates with an annular seat 64 surrounding the entrance to restriction 60. The valve 61 is also provided with an elongated projection 65 of somewhat smaller cross-section than the restriction 60. This projection extends completely thru the jet or restriction 60 when the valve 61 is closed against the seat 64 as shown in the drawing.

15 A spring 66 biases the valve 61 to closed position. The valve 61 may be opened against the force of spring 66 by a pair of electro-magnetic coils 67 and 68. When the coil 67 is energized, the valve 61 is moved to a partly open position, wherein the main body portion of valve 61 is separated from the seat 64, but the projection 65 extends into and partially obstructs the restriction 60. When the coil 68 is also energized, the valve 61 is moved farther to the left from the position shown, to a point where the projection 65 is completely withdrawn from the jet 60, which is then fully opened.

In the system shown in Figure 1, the energization of coil 67 is controlled either by an altitude responsive switch unit 31 or by an attitude responsive switch 70. The energization of coil 68 is controlled by an air flow responsive switch 22. The switch units 22 and 31 are both located in a casing 71, in which they are separated by a wall 69, apertured at 91.

35 The switch 31 is in the lower portion of casing 71, which is divided by a flexible diaphragm 72 into a pair of expandable chambers 30 and 73. The diaphragm 72 carries at its center a bridging contact 74, which cooperates with a pair of stationary contacts 75 and 76. A compression spring 77 biases the diaphragm 72 in a direction to separate contact 74 from the stationary contacts 75 and 76. The chamber 30 is connected through a conduit 32 to the chamber 27 of fuel regulator 25. The chamber 73 is connected thru a conduit 78 to the chamber 33. Therefore the pressure difference between the chambers 30 and 73 is determined by the pressure differential across valve 36. This pressure differential varies with the altitude of the aircraft, since the valve 36 is operated by bellows 35 in accordance with the density of the air. As the altitude increases, the bellows 35 expands moving the valve 36 toward closed position, and thereby increasing the pressure differential between chambers 30 and 73. The diaphragm 72 then moves downwardly against spring 77. When the aircraft rises above a predetermined altitude, the bridging contact 74 engages contacts 75 and 76. The pressure differential between chambers 60 30 and 73 also varies with the quantity of air flowing thru the passage 12. Therefore, the altitude at which the contacts of switch unit 31 are closed varies with the air flow. The altitude and air flow characteristics of the switch may be determined by the characteristics of spring 77. For example, the spring 77 may be chosen so that at sea level, even with maximum air flow, the switch contacts are not closed. On the other hand, the spring 77 may be chosen so that at sea level, the switch closes when a predetermined air flow, which may be that indicated by the ordinate passing thru the point 100 in Figure 2, is exceeded. Then at any other altitude, above sea level, the switch closes at a lower value of air flow.

The attitude responsive switch 70 is illustrated

as a pendulum 80 carrying a movable contact 81 which cooperates with a stationary contact 82. The pendulum 80 is arranged so that when the aircraft tilts upwardly, as in climbing, the contact 81 is moved to engage contact 82.

When an aircraft is in its normal flying position, the lifting force produced by the movement of the air past the wings is a maximum, and the frictional resistance of the wing to movement thru the air is a minimum. In other words, the lift-to-drag ratio of the aircraft is a maximum. As the aircraft departs from this normal flying position, the lifting force is decreased and the drag is increased. With a given horsepower output from the engine, the speed of the aircraft will be a maximum when the lift-to-drag ratio is a maximum. As the lift-to-drag ratio changes, due to climbing of the aircraft or from other causes such as improper load distribution, the speed of the aircraft for a given power output is decreased. As the air speed decreases, the flow of cooling air over the engine decreases. Likewise, in an aircraft having a liquid cooled engine, the flow of cooling air thru the radiator decreases. It may therefore be stated that the attitude of the aircraft, as measured by the pendulum 80 is an indication of the variation in the cooling of the engine.

The pendulum 80 is also affected by acceleration and deceleration of the aircraft. The action of the pendulum in response to acceleration is to increase the fuel-to-air ratio upon acceleration, and to decrease the fuel-to-air ratio upon deceleration. It therefore tends to increase the fuel-to-air ratio as the power output of the engine increases and to decrease the fuel-to-air ratio as the power output decreases. The effect of the response of the pendulum 80 to acceleration is therefore beneficial, although it is incidental to the primary object of the present invention.

The altitude switch 31 is an indication of the effectiveness of the air flowing past the engine or radiator as a cooling agent. The thermal conductivity of the air varies with its density. As the air density decreases at high altitudes, it becomes less efficient as a medium for transferring heat from the engine. The engine therefore tends to run hotter.

When either the altitude or the attitude of the aircraft assumes a value which indicates the presence of adverse cooling conditions, one of the switches 31 or 81 is closed. As described in detail hereinafter, closure of either of these switches causes an enrichment of the mixture of fuel and air supplied to the engine, which lowers the engine operating temperature.

The air flow switch unit 22 is in the upper portion of casing 71, which is separated by a diaphragm 84 into expandable chambers 21 and 85. The diaphragm 84 carries at its center a bridging contact 86 which cooperates with a pair of stationary contacts 87 and 88. A compression spring 90 biases the diaphragm 84 in a direction to separate the contact 86 from the stationary contacts 87 and 88. The chamber 21 is connected thru conduit 23 to chamber 24 in the fuel regulator 25. Chamber 85 is connected thru the aperture 91 to chamber 30 and thence thru conduit 32 to chamber 27 in fuel regulator 25. The pressure differential between chambers 21 and 85 is therefore the same as that existing between chambers 24 and 27. As previously described, this pressure differential is a measure of the mass of air flowing thru the passage 12. When the quantity of air flowing thru passage 12 exceeds a predetermined

value, contact 86 is moved downwardly and bridges the contacts 87 and 88.

The pressure regulator 42 is provided to maintain the pressure on the downstream side of the jet system 40 at a value greater than atmospheric. The pressure regulator 42 includes a diaphragm 93 separating a pair of expandable chambers 94 and 95. The diaphragm 93 carries at its center a valve 96. A compression spring 97 biases the diaphragm 93 for movement of the valve 96 to closed position. The chamber 94 is vented thru a passage 98 to conduit 20 and thence to vent ring 18 and impact tubes 17. The spring 97 maintains the pressure in chamber 95 at a value greater than the atmospheric pressure in chamber 94. In this way, it is assured that the fuel issues from nozzle 16 at a pressure greater than that in the passage 12, thereby minimizing any tendency of the fuel to vaporize in the conduit 43 or nozzle 13.

Operation of Figure 1

When the aircraft is operated in level flight under altitude and air flow conditions such that switch unit 31 does not close its contacts, the relationship between the fuel and air ratio and the air flow is illustrated by the curve A in Figure 2. As the air flow increases from zero, fuel flows only thru the jet 56 until the point 100 on curve A is reached. At that value of air flow, the fuel differential pressure across the jet 57 becomes sufficient to open valve 58 against the tension of spring 63. The fuel and air ratio then becomes increasingly rich as the air flow increases, this enriching of the mixture being limited by the fixed restriction 62. The foregoing operation takes place only when the spring 76 is chosen so that switch 31 does not close its contacts, even at maximum air flow, at the particular altitude considered.

When the aircraft is operating under altitude and air flow conditions such that switch 31 is closed, or when it is climbing, the relation of fuel and air ratio to the air flow is illustrated by the curve B in Figure 1. For example, assume that the aircraft is operating at an altitude and air flow such that the switch 31 moves contact 74 into engagement with contacts 75 and 76. An energizing circuit for coil 67 is then completed, which may be traced from the upper terminal of a battery 101 thru a conductor 102, contacts 75, 74 and 76, a conductor 103, a conductor 104, coil 67, a conductor 105, to the lower terminal of battery 101. Energization of coil 67 causes valve 61 to move off its seat, and the jet 60 is then partially opened, being restricted only by the projection 65.

When the air flow increases beyond the value indicated by the point 106 on curve B, the switch 22 moves contact 86 into engagement with contacts 87 and 88. This completes an energizing circuit for coil 68, which may be traced from the upper terminal of battery 101 thru conductor 102, contacts 75, 74 and 76, conductors 103 and 107, contacts 87, 86 and 88, a conductor 108, coil 68 and a conductor 110 to the lower terminal of battery 101. Energization of coil 68 causes projection 65 to be completely moved out of jet 60, thereby enriching the fuel and air mixture as indicated by the curve B between the points 106 and 111.

When the air flow reaches the value indicated by the point 111 in curve B, the valve 58 opens, further increasing the fuel and air ratio.

It will be noted that the effect of the attitude

switch 70 on the operation of the system is the same as that of altitude switch 31 since the two are connected in parallel. It is therefore believed it will be unnecessary to describe the operation of switch 70 in any detail.

Operation of Figure 3

There is shown in Figure 3 a switch mechanism which is operated in accordance with the rate of change of altitude of an aircraft. This switch mechanism may be substituted for the altitude switch 70 of Figure 1. Referring to Figure 3, there is shown a generally cylindrical casing 200 attached to a base 201 by any suitable means such as the bolts 202. Inside the casing there is mounted on the base 201 a flexible bellows 203. A spring 204 is compressed between the bellows 203 and the base 201. A pair of guide members 205 and 206 project from the base 201 and maintain the spring 204 in proper alignment. The exterior of bellows 203 is exposed to atmospheric pressure thru a suitable aperture 199 in the casing 200. A passage 207 extends horizontally from the space adjacent the exterior of bellows 203 to a vertical passage 208 which extends upwardly thru the base 201 and is concentric with the bellows 203 and an elongated nozzle 210 connecting the passage 208 with the interior of bellows 203. The passage thru nozzle 210 is of a very narrow cross-section, and restricts the flow of air between the exterior and interior of bellows 203.

As long as the aircraft is operating at a constant altitude the pressures inside and outside the bellows 203 are equal. When the aircraft changes its altitude, for example by climbing, the pressure outside the bellows decreases due to the increase in altitude. This change in pressure is not immediately communicated to the interior of bellows 203 because of the restriction in nozzle 210. Since the pressure inside the bellows 203 is then greater than the pressure outside, the bellows tends to expand. The force acting to expand the bellows is proportional to the rate of change of altitude of the aircraft.

A rod 211 is mounted on the free upper end of the bellows 203. The rod 211 extends thru a bushing 212 in a portion of a casing 200, and near its upper end carries a movable switch contact 213 which cooperates with a stationary contact 214. The structure is such that when the aircraft is flying level the contact 213 is below and spaced from the contact 214, as shown in the drawing. When the aircraft starts to rise, the contact 213 is moved upwardly by an amount depending upon the rate of climb. When the rate of climb exceeds a value determined by the characteristics of the bellows 203 and spring 204, contact 213 is moved into engagement with contact 214. This completes a circuit between terminals 115 and 116, which correspond to the terminals having the same reference numerals in Figure 1.

Stationary contact 214 is in the form of a disc mounted between two insulating plates 215, which are held on the top of the casing 200 by bolts 216. The circuit between terminals 115 and 116 may be traced from terminal 115 thru a conductor 217, a connector 218, a conductor 220, binding post 221, casing 200, rod 211, contacts 213 and 214, a conductor 222, connector 218 and a conductor 223 to terminal 116.

The operation of the system when the switch unit shown in Figure 3 is used therein is similar to the operation when the switch unit 70 is used,

and it is believed no further description of this operation is necessary.

It should be noted that the switch mechanism of Fig. 3 and the switches 31 and 70 of Fig. 1 are responsive to conditions which affect the thermal capacity of the air passing the engine and therefore affect the rate at which heat can be dissipated from the engine. This is true of both air cooled and water cooled engines. Water cooled engines depend for their ultimate cooling on the ability of a radiator to dissipate heat to the outside atmosphere. As the density of the air decreases, its specific heat decreases and, therefore, the thermal capacity of a given volume of it decreases. It is, therefore, not possible to dissipate as much heat from the engine. Similarly, when the aircraft is climbing, its forward speed is slower and the quantity of air passing the engine is decreased so that the thermal capacity of the air is decreased and it cannot be cooled as efficiently. Under such conditions, it is desirable to enrich the mixture of fuel-to-air supplied to the engine so that its temperature will not rise as high.

While I have shown and described certain preferred embodiments of my invention, other modifications thereof will readily occur to those skilled in the art, and I therefore intend that my invention shall be limited only by the appended claims.

I claim as my invention:

1. In a fuel supply system for an internal combustion engine, a conduit for air flowing to said engine for combustion purposes, means associated with said conduit for producing two unequal pressures whose difference is a measure of the rate of flow of air thru said conduit, a conduit for fuel flowing to said engine, a metering restriction in said fuel conduit for regulating the flow thru said fuel conduit as a function of the fuel pressure differential across said restriction, means for controlling said fuel pressure differential as a function of the difference of said two unequal pressures so as to maintain a substantially constant fuel-to-air ratio as long as the cross-sectional area of said metering restriction remains fixed, means responsive to said fuel pressure differential for increasing the cross-sectional area of said restriction when said differential exceeds a predetermined value to increase said fuel-to-air ratio, and additional means responsive to a condition affecting the thermal capacity of the air passing said engine for increasing the cross-sectional area of said restriction to increase said fuel-to-air ratio when said condition assumes a predetermined value indicative of insufficient cooling of said engine.

2. In a fuel supply system for an internal combustion engine, a conduit for air flowing to said engine for combustion purposes, means associated with said conduit for producing two unequal pressures whose difference is a measure of the rate of flow of air thru said conduit, a conduit for fuel flowing to said engine, a metering restriction in said fuel conduit for regulating the flow thru said fuel conduit as a function of the fuel pressure differential across said restriction, means for controlling said fuel pressure differential as a function of the difference of said two unequal pressures so as to maintain a substantially constant fuel-to-air ratio as long as the cross-sectional area of said metering restriction remains fixed, and means responsive to a condition affecting the thermal capacity of the air passing said engine for suddenly and substantially increasing the cross-sectional area of said restriction to

increase said fuel-to-air ratio when said condition assumes a predetermined value indicative of insufficient cooling of said engine.

3. In a fuel supply system for an internal combustion engine, a conduit for air flowing to said engine for combustion purposes, a conduit for fuel flowing to said engine, means for controlling the relationship of said air and fuel flows to maintain a substantially constant fuel-to-air ratio, and means responsive to a condition affecting the thermal capacity of the air passing said engine for suddenly and substantially increasing said fuel-to-air ratio when said condition assumes a predetermined value indicative of insufficient cooling of said engine.

4. In a fuel supply system for an internal combustion engine, a conduit for air flowing to said engine for combustion purposes, a conduit for fuel flowing to said engine, means for controlling the relationship of said air and fuel flows to maintain a substantially constant fuel-to-air ratio, means responsive to the load on said engine and effective when said load exceeds a predetermined value to increase said fuel-to-air ratio, and additional means responsive to a condition affecting the thermal capacity of the air passing said engine for suddenly and substantially increasing said fuel-to-air ratio when said condition assumes a value indicative of insufficient cooling of said engine.

5. In a fuel supply system for an aircraft internal combustion engine, a conduit for air flowing to said engine for combustion purposes, means associated with said conduit for producing two unequal pressures whose difference is a measure of the rate of flow of air thru said conduit, a conduit for fuel flowing to said engine, a metering restriction in said fuel conduit for regulating the flow thru said fuel conduit as a function of the fuel pressure differential across said restriction, means for controlling said fuel pressure differential as a function of the difference of said two unequal pressures so as to maintain a substantially constant fuel-to-air ratio as long as the cross-sectional area of said metering restriction remains fixed, means responsive to said fuel pressure differential for increasing the cross-sectional area of said restriction when said differential exceeds a predetermined value to increase said fuel-to-air ratio, and additional means responsive to the rate of climb of said aircraft for suddenly and substantially increasing the cross-sectional area of said restriction to increase said fuel-to-air ratio when said rate of climb assumes a value indicative of insufficient cooling of said engine.

6. In a fuel supply system for an aircraft internal combustion engine, a conduit for air flowing to said engine for combustion purposes, a conduit for fuel flowing to said engine, means for controlling the relationship of said air and fuel flows to maintain a substantially constant fuel-to-air ratio, and means responsive to the rate of climb of said aircraft for suddenly and substantially increasing said fuel-to-air ratio when said rate of climb assumes a value indicative of insufficient cooling of said engine.

7. In a fuel supply system for an aircraft internal combustion engine, a conduit for air flowing to said engine for combustion purposes, a conduit for fuel flowing to said engine, means for controlling the relationship of said air and fuel flows to maintain a substantially constant fuel-to-air ratio, means responsive to the load on said engine and effective when said load exceeds

a predetermined value to increase said fuel-to-air ratio, and additional means responsive to the rate of climb of said aircraft for increasing said fuel-to-air ratio when said rate of climb assumes a value indicative of insufficient cooling of said engine.

8. In a fuel supply system for an internal combustion engine, a conduit for air flowing to said engine for combustion purposes, means associated with said conduit for producing two unequal pressures whose difference is a measure of the rate of flow of air thru said conduit, a conduit for fuel flowing to said engine, a metering restriction in said fuel conduit for regulating the flow thru said fuel conduit as a function of the fuel pressure differential across said restriction, means for controlling said fuel pressure differential as a function of the difference of said two unequal pressures so as to maintain a substantially constant fuel-to-air ratio as long as the cross-sectional area of said metering restriction remains fixed, valve means for controlling the cross-sectional area of said restriction, electrical means for operating said valve means including a pair of electrical circuits, first motor means connected in one of said circuits and effective when said circuit is completed to move said valve means to a partly open position, second motor means connected in the other of said circuits and effective when said other circuit is completed to move said valve means to a fully open position, first switch means connected in both said circuits, means responsive to a condition affecting the thermal capacity of the air passing said engine for closing said first switch means and thereby completing said one circuit, second switch means connected in said other circuit in series with said first switch means, and means responsive to the rate of flow of combustion air to said engine for closing said second switch means and thereby completing said other circuit when said first switch means is also closed.

9. In a fuel supply system for an internal combustion engine for use on aircraft, in combination, a plurality of parallel conduits for conveying fuel to said engine, valve means for controlling the flow of fuel thru one of said conduits, means biasing said valve means to closed position, electrical means for operating said valve means selectively to an intermediate position or to its full open position against the action of said biasing means, first switch means for controlling the energization of said electrical means, said first switch means being effective when closed to cause energization of said electrical means so as to operate said valve means to said intermediate position, means responsive to a condition affecting the thermal capacity of the air passing said engine for operating said first switch means to closed position when said condition assumes a value indicative of insufficient cooling of said engine, second switch means for controlling the energization of said electrical means, said second switch means being effective when closed to cause energization of said electrical means so as to operate said valve means to said full open position, and means responsive to the quantity of air for combustion purposes flowing to said engine for operating said second switch means.

10. In a fuel supply system for an internal combustion engine for use on aircraft, in combination, means for controlling the flow of fuel to said engine in proportion to the quantity of air flowing to said engine, first means for increasing the ratio of fuel to air, second means for addi-

tionally increasing the ratio of fuel to air, means responsive to a condition affecting the thermal capacity of the air passing said engine for operating said first means when said condition assumes a value indicative of insufficient cooling of said engine, and means responsive to the quantity of air flowing to said engine for operating said second means when said quantity exceeds a predetermined value.
